JET PROPULSION PLANT

Roger Jean Imbert, Paris, France, assignor to
 Societe Rateau (Societe Anonyme), Paris,
 France, a company of France and Rene
 Anxiomnaz, Paris, France, jointly

Application March 19, 1947, Serial No. 735,676
 In France April 2, 1946

9 Claims. (Cl. 60—35.6)

1

In the prior U. S. Patent 2,396,911 of which I am one of the applicants, and relating to jet propulsion plants for aircraft, there is described a plant in which the cylinders of an internal combustion reciprocating engine driving the air compressor are cooled by the flow of air passing through the propulsion nozzle. The output of air required for propelling purposes is substantially higher than the amount of air which is sufficient for ensuring this cooling. It is therefore necessary to improve the efficiency of the propeller by limiting the output of the cooling air to its optimum value. The arrangements which are capable of ensuring a limitation of this flow and improving the cooling conditions of the engine form the object of the U. S. application Serial No. 643,028 filed by Marcel Sédille on January 24, 1946, for "Improvements in Reaction Propellers." In this application, the flow of air delivered by the compressor is divided into two parts of which one is projected towards the periphery and enters the propulsion nozzle directly while the second, separated from the former by a suitable partitioning, is submitted to the action of a booster or fan which is to make up for the loss of pressure in the cooling circuit and this second air flow passes through the compartment occupied by the cylinders of the engine and ensures the cooling thereof.

My present invention has for its object an improvement in the arrangement disclosed hereinabove based on the separation between the two flows, but it simplifies the arrangement by doing away with the auxiliary fan and ensures a greater adaptability in the operation of the plant.

The arrangement according to my invention also includes a partition separating the two flows, but with an extension thereof to a point at which the drop in pressure in the two circuits becomes equal and it also allows using a movable member adapted to modify the output of the cooling flow in accordance with the temperature of the engine.

The following description and corresponding accompanying drawing given by way of example and by no means in a limitative sense will allow a better understanding of my invention.

In said drawing:

Fig. 1 is a diagrammatic axial cross-section of a propeller executed in accordance with my invention and incorporating means for adjusting the cooling flow at the output of the propeller.

Fig. 2 is a diagrammatic axial cross-sectional view of a modification of the adjusting means for adjusting the cooling flow.

Fig. 3 is a diagram showing the positions of the adjusting member illustrated in Fig. 2 corresponding to equilibrium between the pressure of both gaseous flows.

2

Fig. 4 illustrates a combination of the adjustment of the output and of the cooling flow and of the adjustment of the outer flow.

Fig. 5 shows in partial cross-section, on an enlarged scale, the manner in which the device of Fig. 4 may be controlled.

Fig. 6 illustrates a temperature measuring device positioned in the engine.

In the first arrangement, Fig. 1 shows at *a* an air compressor and at *c* the reciprocating engine which drives said compressor. The air delivered by the compressor is divided into two separate flows by a partition *b*, said partition extending in this case up to the propulsion nozzle.

15 The inner flow is led by the partition to the engine *c* for cooling the same. The outer flow is led directly to the propulsion nozzle.

In the figure, the cooling flow receives past the engine *c* the exhaust gases from the said engine *c* but these gases might as well be discharged into the outer flow. It will be noted that it is possible to heat the outer flow through the agency of the combustion chambers *e* and to heat the inner flow through burners *d* arranged between the engine and the propulsion nozzle.

25 The adjustment of the cooling flow is obtained by a movable obturator or throttle member *f* of suitable outline adapted to move axially so as to modify the output cross-section of the nozzle *b* of the cooling circuit. This throttle member is shown in its maximum opening position in the upper half of the cross-section and in its throttling position in its lower half cross-section.

The translational movement of this throttle member is ensured through any known means 35 such as a piston *g* controlled in its turn by a distributor *h* under the action of a thermostat *k* actuated by the temperature of a delicate part of the engine such as a valve seat. Any other form of execution may be adopted as well.

40 This adjustment allows for instance keeping substantially constant the engine cooling current in spite of any variation in the drop of pressure in the outer circuit, which drop in pressure may vary according to the rate of heating of the outer 45 flow through the combustion performed at the burners *e*.

This allows therefore maintaining at suitable values the temperature of the engine and this latter variable factor may be used as disclosed 50 hereinabove as a base for the adjustment obtained with the obturator *f*.

Another possible embodiment of my invention is shown in Fig. 2. In this case, the free cross-section area for the cooling flow is not modified 55 as in the preceding case, but the point at which this cooling flow mixes with the outer flow is dis-

3

placed inside the expansion nozzle or in other words the pressure prevailing in the outlet of the cooling flow is modified to vary the output of cooling flow in accordance with the value of the said pressure.

The arrangement allowing this variable condition assumes for instance the shape of a cylindrical ferrule *l* adapted to move inside the exhaust nozzle with a translational movement and to this purpose the partition *m* ends with a cylindrical part *m*₁ serving as a guide for the ferrule *l*.

In Fig. 2 the exhaust *c*₁ of the engine *c* is connected with the chamber used for the outer flow, but it may as well open into the cooling flow downstream of the engine as in the case of Fig. 1.

The desired balance of pressure in the mixing cross-section of the two gasiform flows of the arrangement illustrated in Fig. 2 is checked by means of the graph of Fig. 3; starting from a static pressure prevailing at point *i* corresponding to the entrance of the air at *A* into the plant, I obtain a pressure *j* at the output of the last wheel of the compressor. The pressure curve for the outer flow, illustrated by the curve *o* when said flow has not been heated, rises up to point *j*₁ by reason of a slowing down effect in the channel following said last wheel after which it slopes downwardly until it reaches the point *n* where the static pressure is equal to the ambient pressure and corresponding to the output end of the propulsion nozzle. When the outer flow includes means for heating through combustion by means of burners *e*, the curve follows the dotted outline *o*₁ underneath the line *o* preceedingly considered by reason of an increase of the speed of flow.

The pressure curve of the cooling flow is shown at *r* when no heating of this flow is provided and at *r*₁ when the flow is submitted to a heating through a combustion operated by the burners *d*.

The corresponding curves of the outer flow and of the cooling flow cross one another at four points: *v*, *x*, *y*, *z* which define the respective positions to be occupied by the adjusting ferrule *f*, when the pressures of both flows at the mixing point are to be maintained equal, according to the rate of running of the plant. Of course, for a suitable position of the ferrule *l*, it is possible, however, to have, at the mixing point, in the outer flow a pressure greater or smaller than that of the cooling flow and to vary in this manner the output of the cooling flow.

In my copending application Serial Number 643,027 filed on January 24, 1946, now Patent No. 2,557,435, for "Regulating devices for the outlet section of a reaction propeller tube or nozzle," I have described a telescopic nozzle adapted to move axially with reference to the reaction nozzle. Fig. 4 shows how it is possible with such a nozzle to associate the adjustment of the position of the output nozzle of the cooling flow of gasiform fluid with the reduction in cross-section of the output nozzle of the outer flow, said association giving a still greater adaptability to the operation of the propulsion plant.

In this case, it is possible to use the movable ferrule *l* of Fig. 2, but the latter instead of sliding directly inside the cylindrical end *m*₁ of the partition separating the gasiform flows is carried inside an intermediary ferrule *t* rigid with a nozzle *u* executed in accordance with the arrangement disclosed in the last mentioned application referred to hereinabove.

This arrangement allows obtaining the extreme positions shown in the lower and higher cross-sections, and also any intermediary position be-

4

tween the latter, both as concerns the telescoping ferrule *t* and the ferrule *l*.

The ferrule or sleeve *l* may be controlled automatically from a piston *g* (Fig. 5) in a cylinder to which a pressure fluid is admitted under the control of a valve *h* which is actuated by a heat sensitive element *k* exposed to the temperature of a component part of the engine.

The intermediate ferrule or sleeve *t* fast with the propulsion nozzle throttle *u* may be provided with control means comprising a piston *g*₁ the hollow rod *g*₂ of which slides on the rod of piston *g* while the pressure fluid valve therefor is at *h*₁; said valve may be actuated in any manner, for example by hand.

What I claim is:

1. In a jet propulsion plant of the type comprising air compressing means having at least one compression stage, an internal combustion reciprocating engine driving said air compressing means, and a propulsion nozzle fed by said air compressing means for producing the motive jet; an annular partition beginning at the delivery side of the said air compressing means 20 after the last compressing stage of said air compressing means for dividing the air delivered by the last compression stage into two separate flows, one of which is led inside said partition around the engine for cooling the same, and the other 30 of which is by-passed outside of said partition towards the propulsion nozzle, said partition having a discharge end near the propulsion nozzle, heating means outside of said partition between the said last stage and the discharge end of the 35 partition for heating said second mentioned flow, and means near the discharge end of said partition for regulating the cooling flow inside said partition.

2. The combination of claim 1, wherein heating means are provided in the cooling flow between the engine and the end of said partition.

3. The combination of claim 1, wherein the regulating means for the cooling flow comprises a movable throttling member for varying the output of the cooling flow.

4. The combination of claim 1 comprising further temperature sensitive means arranged in the vicinity of the valves of the said engine, the regulating means for the cooling flow being controlled by said temperature sensitive means.

5. In a jet propulsion plant of the type comprising air compressing means having at least one compression stage, an internal combustion reciprocating engine driving said means, and a propulsion nozzle fed by said compressing means for producing the motive jet; a partition beginning at the delivery side of the said compressing means after the last compression stage thereof for dividing the air delivered by said stage into two separate flows, one of which is led inside said partition around the engine for cooling the same, and the other of which is by-passed outside said partition towards the propulsion nozzle, said partition having a discharge end near the propulsion nozzle, heating means provided in the outer by-passed flow as well as in the cooling flow between the engine and the discharge end of the partition and a movable throttling member arranged near the discharge end of the said partition for varying the output of the cooling flow inside said partition.

6. In a jet propulsion plant of the type comprising air compressing means having at least one compression stage, an internal combustion reciprocating engine driving said air compressing

means, and a propulsion nozzle fed by said air compressing means for producing the motive jet; an annular partition beginning at the delivery side of the said air compressing means after the last compression stage for dividing the air delivered by the last compression stage into two separate flows, one of which is led inside said partition around the engine for cooling the same, and the other of which is by-passed outside said partition towards the propulsion nozzle, said partition having a discharge end ahead of the propulsion nozzle, heating means outside of said partition for heating the second mentioned flow, and a movable ring at the discharge end of said partition for variably prolonging the same towards the propulsion nozzle, said ring having a diameter less than that of the outlet port of said nozzle, so that an annular passage for the outer by-passed flow remains open between said ring and said nozzle for each position of said ring.

7. The combination of claim 6, wherein heating means are also provided in the cooling flow between the engine and the end of said partition.

8. The combination of claim 6, wherein the movable ring comprises at least two parts annular telescopically arranged, one of said parts having further an annular nozzle adapted to cooperate

with the propulsion nozzle for varying the cross-section area thereof.

5 9. The combination of claim 6, comprising further temperature sensitive means arranged in the vicinity of the valves of the said engine, the displacement of the said movable wall being controlled by said temperature sensitive means.
